UNITED STATES PATENT OFFICE.

WILLIAM WARNER, OF MELVERN, KANSAS.

DESIGN FOR A FENCE-PANEL.

SPECIFICATION forming part of Design No. 25,805, dated July 21, 1896.

Application filed February 29, 1896. Serial No. 581,408. Term of patent 14 years.

To all whom it may concern:

Be it known that I, WILLIAM WARNER, a citizen of the United States, residing at Melvern, in the county of Osage and State of Kansas, have invented a new and original Design 5 for Woven-Wire Fence-Panels, of which the following is a specification.

This invention relates to a new and original design for woven-wire fence-panels; and 10 it has for its object to provide a design of this character that shall be both useful and ornamental.

The leading feature of the design resides in a woven-wire fence-panel having a series 15 of vertically and horizontally disposed wires intersecting with each other to form vertically and horizontally aligned rows of rhomboidal-shaped figures whose upper and lower sides are disposed at an angle to a horizontal plane, 20 the rhomboidal-shaped figures in the upper and lower horizontal rows being bounded at one side by twisted strands, and the remaining rhomboidal-shaped figures being each bounded at diagonally opposite corners by 25 short obliquely-disposed twisted-wire sections.

In the drawing the figure is a plan view of a woven-wire fence-panel embodying the herein-described design.

Referring to the accompanying drawing, the 30 numerals 1 and 2 designate vertically and horizontally disposed wires intersecting with each other to form vertically and horizontally aligned rows of rhomboidal-shaped figures 3, whose upper and lower sides are disposed at 35 an angle to a horizontal plane. The rhomboidal-shaped figures 3 in the upper and lower horizontal rows of such figures are bounded at one side by twisted strands 4, which twisted strands 4 are provided with a series of pointed 40 projections 5. The remaining rhomboidal-shaped figures 3 are each bounded at diagonally opposite corners by short obliquely-disposed twisted-wire sections 6, and the rhomboidal-shaped figures below the horizontal 45 center of the panel are all of a smaller area than those above the horizontal center of the panel.

What I claim is—

The design for a woven-wire fence-panel 50 herein shown and described.

In testimony that I claim the foregoing as my own I have hereto affixed my signature in the presence of two witnesses.

WILLIAM WARNER.
